ATTORNEY

UNITED STATES PATENT OFFICE.

FRANZ A. FULLER, OF NEWARK, NEW JERSEY, ASSIGNOR TO THE J. E. MERGOTT CO., OF NEWARK, NEW JERSEY, A CORPORATION OF DELAWARE.

BLOTTER.

1,422,555.

Specification of Letters Patent. Patented July 11, 1922.

Application filed August 27, 1921. Serial No. 496,000.

To all whom it may concern:

Be it known that I, FRANZ A. FULLER, a citizen of the United States, residing at Newark, in the county of Essex and State 5 of New Jersey, have invented new and useful Improvements in Blotters, of which the following is a specification:

One of the objects of this invention is to provide a convenient form of blotter, of the 10 handled, rocking type, in which the blotter backing is essentially rigid, enabling a firm and effective application to be made.

Another purpose is to produce a blotter of the type mentioned comprised of merely 15 two metallic elements, respectively a support frame and handle, interlockingly engaged in a novel and positive manner.

A further object is in the provision of a neat, strong and durable blotter at a moderate 20 cost.

These objects are attained by the novel design, construction and arrangement of parts, hereinafter described and shown in the accompanying drawing, forming a material 25 part of this disclosure and in which:—

Figure 1 is a perspective view of a blotter made in accordance with the invention.

Figure 2 is a partial side elevational, partial 30 sectional view of the same, the section being taken on line 2—2 of Figure 3.

Figure 3 is a bottom plan view thereof.

Referring to the drawing, the numeral 10 designates in general the frame or backing of the blotter, the same consisting of an elongated 35 rectangular sheet of thin metal, as bronze, bent to form an arc of a circle and having raised transverse ridges 11 curved semi-circularly at their outer edges into loops 12 which merge into reverse elements 40 13 spaced parallel from the ridges 11 and terminating in out-turned bevel edges 14, leading to the recesses or sockets 15 formed by the transverse bends.

Equi-distant from the center of the curved 45 plate are a pair of narrow raised ribs 16 extending from one of the ridges 11 to the other into which they blend.

Closely adjacent the inner sides of each 50 rib, in transverse alignment, are a plurality of narrow rectangular slots 17 arranged in pairs, the outer of which are relatively close to the ridges and the intermediate pairs disposed at intervals therebetween.

The plate material at the inner side of 55 each slot 17 is stamped to extend to about

the height of the ribs 16, the width of these projections being equal to the length of the slots and their inner, adjacent edges are sharply defined in semi-circular contour, presenting depressions or recesses 18 in the lower convex side of the plate.

The handle is composed of a flat rectangular plate 20 having sides 21 bent sharply at a right angle, the contour of the side edges being arcuate to conform to the curve of the 65 backing plate 10.

Formed to extend outwardly from the side element 21, spaced parallel with the top surface 20, are extending ribs 22, the same materially assisting in obtaining a firm grasp 70 upon the handle.

Extending radially outward from the curved edges of the handle side elements are a plurality of prongs or projections 23 suited to pass through the slots 17 and then be bent 75 laterally to fill the depressions 18 in which they are eventually clinched.

This operation draws the curved edges of the handle sides into intimate relation with the inner sides of the ribs 16 and concave 80 surface of the plate 10, forming a rigid reinforcement, and the clenched prongs, filling the depressions 18, thus providing a substantially smooth convex surface against which may be placed a felt pad or cushion 85 24 to receive the blotting paper, or like material, the same being held in operative position by inserting its ends into the recesses 15.

Thus a firm, easily operated rocking blotter has been disclosed, the operation of 90 which, after assembly is considered so obvious as to require no further explanation.

Although the foregoing is descriptive of the preferred embodiment of the invention, it will be apparent that minor changes may 95 be made in its construction, without the exercise of invention or conflicting with the scope of the claims hereto appended.

Having thus described my invention, what I claim as new and desire to secure by Letters Patent, is:—

1. A blotter comprising a curved plate frame having means at its ends for engaging blotter material said frame containing two rows of spaced paired slots, a metal handle 105 conforming to the concave side of said frame, prongs extending from the edges of said handle engaged in the mentioned slots and clenched in depressions adjacent the slots in the convex side of said frame. 110

2. A blotter comprising an arcuately bent plate having reversed end edges forming recesses receptive of blotter material, ribs extending longitudinally of said plate raised on the concave side thereof, a rigid hollow handle made of sheet metal with arcuate sides conforming to said bent plate, ribs on the sides of said handle, said sides fitting between the ribs of said plate, and means formed with said sides interlocking in openings in said plate.

3. A blotter comprising an oblong rectangular metallic plate having a uniform arcuate curve, open transverse loops at the ends of said plate, a pair of spaced ribs raised on the concave side of said plate extending from end to end thereof, depressed seats arranged in paired intervals inter-

20 jacent said ribs there being open slots intervening said seats and ribs, a handle formed of sheet metal having a flat top and right-angled sides cut to fit said plate between said ribs, outstanding ribs on the sides of said handle, and prongs extending radially from the arcuate edges of said handle sides 25 through the mentioned slots and clenched upon said seats thereby forming a substantially level bottom on the convex side of said blotter plate.

This specification signed and witnessed 30 this 26th day of August, 1921.

FRANZ A. FULLER.
